United States Patent Office

Des. 191,580
Patented Oct. 17, 1961

191,580

ELECTRIC CAN OPENER

Robert N. Freedman, Great Neck, N.Y., assignor to Vogue Electronic & Appliance Corp., a corporation of
New York

Filed Mar. 8, 1961, Ser. No. 64,189

Term of patent 3½ years

(Cl. D22—2)

FIG. 1

FIG. 2

FIG. 3

FIGURE 1 is a perspective view of an electric can opener, showing my new design;

and

FIGURE 4 is an elevational view of the other side thereof.

I claim:

The ornamental design for an electric can opener, substantially as shown.
